(57) **CLAIM**

The ornamental design for a cover for vehicle seats, as shown and described.

DESCRIPTION

FIG. 1 is a top perspective view of a cover for vehicle seats in a partially folded configuration in accordance with the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top plan view of the cover for vehicle seats in an unfolded configuration; and,

FIG. 9 is a bottom plan view thereof.

(Continued)

The broken lines in the drawings depict portions of the cover for vehicle seats that form no part of the claimed design.

1 Claim, 6 Drawing Sheets
